UNITED STATES PATENT OFFICE

EINAR MORTERUD, OF TORDEROD, NEAR MOSS, NORWAY

TOP SCREEN FOR WOOD PULP DIGESTERS OR THE LIKE

Application filed March 19, 1930. Serial No. 437,093.

The present invention relates to wood pulp digesters or the like of the kind which are provided near their top with one or more horizontal screens or sieves for distributing the circulating digesting liquid evenly over the cross sectional area of the digester, and the invention has for its object to provide a screen or sieve of the kind referred to, which will permit the passage of digesting liquid even if the normal screen or sieve openings be clogged, so as to be put out of operation.

This object is attained in accordance with the present invention by providing the screen or sieve surface with passages having a larger diameter than the ordinary holes of the screen, the intake to said passages being raised a certain distance above the level of the screen, in order that they shall operate as overflow passages in case the ordinary openings of the screening surface become wholly or partly clogged.

According to a preferred embodiment of the invention the auxiliary overflow openings in accordance with the present invention are made in the form of short vertical tubes, which extend from the surface of the screen to a short distance above the same, the upper end of said tubes being preferably inclined, so as to afford a passage with gradually increasing capacity, as the level of digesting liquid on the screen rises.

A preferred embodiment of the invention is diagrammatically illustrated on the drawing, which shows a vertical cross sectional view through the top of a wood pulp digester.

1 indicates the shell of the digester, 2 is the intake opening for filling the digester with wood fibers or the like, 3 is the intake for digesting liquid, and 4 is a horizontal distributing screen for distributing the digesting liquid over the cross sectional area of the digester.

Preferably the total cross sectional area of the normal holes 5 in screen 4 is sufficient to permit the passage of the total amount of

digesting liquid as soon as there is a slight head of liquid on the screen.

Should, however, part of the normal openings 5 be clogged for some reason, the liquid level on the screen will rise, and the surplus liquid will then flow over through the overflow tubes 6, a number of which are distributed over the area of the screen, said overflow tubes having a considerably larger diameter than the ordinary screen holes, so that they are not liable to be clogged by impurities. The upper ends of said overflow tubes 6 are preferably cut at an angle as indicated at 7, so as to present a gradually increasing overflow area as the level of liquid rises.

Although the improvement in accordance with the present invention is particularly adapted for wood pulp digesters, it will easily be understood that it may also be utilized in connection with other similar vessels, which are provided at their top with horizontal screen or sieve surfaces for the distribution of liquid over the cross sectional area of the vessel.

Claims:

1. In a wood pulp digester or the like a screen or sieve near the top thereof for distributing liquid evenly over the cross sectional area of the vessel, holes for the passage of liquid distributed over the area of said sieve and auxiliary overflow passages having a larger individual cross sectional area than that of the said holes located a certain distance above the level of the sieve surface.
2. In a wood pulp digester or the like a screen or sieve near the top thereof for distributing liquid evenly over the cross sectional area of the vessel, holes for the passage of liquid distributed over the area of said sieve and tubes passing through said screen or sieve and extending a certain distance above the level thereof so as to provide auxiliary passages for the liquid.
3. In a wood pulp digester or the like a

screen or sieve near the top thereof for distributing liquid evenly over the cross sectional area of the vessel, holes for the passage of liquid distributed over the area of
5 said sieve and tubes passing through said screen or sieve and extending a certain distance above the level thereof so as to provide auxiliary passages for the liquid, the upper end of said tubes being inclined so as to afford
10 overflow passages with gradually increasing capacity.

In testimony whereof I affix my signature.
EINAR MORTERUD.
